DESIGN FOR A GAME BOARD OR SIMILAR ARTICLE

Tee Ka Chay, Brooklyn, N. Y.

Application August 22, 1942, Serial No. 107,999

Term of patent 7 years

To all whom it may concern:

Be it known that I, Tee Ka Chay, a citizen of the Republic of China, residing at 395 Ocean Avenue, Brooklyn, county of Kings, and State of New York, have invented a new, original, and ornamental Design for a Game Board or Similar Article, of which the following is a specification, reference being had to the accompanying drawing, forming part thereof.

In the drawing the figure is a top plan view of a game board or similar article, showing my new design.

The game board is of conventional thickness.

I claim:

The ornamental design for a game board or similar article, substantially as shown and described.

TEE KA CHAY.
